United States Patent Office

Des. 185,288
Patented May 26, 1959

185,288

SERVING SPOON OR THE LIKE

Clifford V. Johnson, Park Ridge, and Arthur Salm, Chicago, Ill., assignors to Arthur Salm Inc., Chicago, Ill., a corporation of Illinois

Application October 13, 1958, Serial No. 52,967

Claims priority, application Germany May 21, 1958

Term of patent 14 years

(Cl. D54—12)

Fig. 1 is a face view of a serving spoon showing our new design;

Fig. 2 is a side view of the serving spoon of Fig. 1;

Fig. 3 is an end view of the serving spoon of Fig. 1;

Fig. 4 is a sectional view of the serving spoon of Fig. 1 taken on the line 4—4 thereof; and

Fig. 5 is a sectional view of the serving spoon of Fig. 1 taken on the line 5—5 thereof.

The dominant features of the design for a serving spoon reside in the portions shown in full lines.

We claim:

The ornamental design for a serving spoon or the like, substantially as shown and described.
